UNSYMMETRICALLY SUBSTITUTED 3,9-DIAZA-
SPIRO(5,5)UNDECANE COMPOUNDS

Charles H. Grogan, Falls Church, Va., and Leonard M. Rice, Baltimore, Md., assignors to The Geschickter Fund for Medical Research, Inc., Washington, D.C., a corporation of New York
No Drawing. Filed May 17, 1962, Ser. No. 196,564
6 Claims. (Cl. 260—293)

The present invention relates to novel heterocyclic nitrogen compounds and, more specifically, to diazaspiranes and to methods for their synthesis.

In applicants' copending application Serial No. 47,613, filed August 5, 1960 (now abandoned), are disclosed several classes of symmetrical 3,9-diazaspiro(5.5)undecane compounds which are particularly useful medicinally. Broadly speaking, the 3,9-diazaspiro(5.5)undecanes disclosed in that application are divided into two classes, the first constituting a symmetrical secondary amine in which a hydrogen atom is attached to each nitrogen atom in the diazaspiro nucleus, the second constituting symmetrical tertiary amines in which both nitrogen atoms are substituted with the same group selected from alkyl and alkylene of 1 to 6 carbon atoms.

The instant application is also directed to 3,9-diazaspiro(5.5)undecanes. Unlike the compounds of Serial No. 47,613, however, the compounds of the instant invention are all unsymmetrical. That is to say, each of the two nitrogen atoms in the diazaspiro nucleus of the compounds of the present invention contains a different substituent.

While the compounds of the present invention are thus superficially related to those of Serial No. 47,613, there are basic fundamental differences between the two, which differences will be discussed in greater detail at a later point in this specification. Broadly speaking, however, it may be said that the compounds of the present invention are much more versatile in their usefulness than are those of Serial No. 47,613 and, in fact, the compounds of the present invention may even be used as an alternate source of preparation of the compounds of Serial No. 47,613. In addition, the compounds of the present invention have a distinct and valuable medicinal utility.

It is accordingly a primary object of the present invention to provide novel, pharmacologically active diazaspiranes and methods for their preparation.

It is another principal object of the present invention to provide unsymmetrical 3,9-diazaspiro(5.5)undecanes which are extremely versatile in their usefulness and which have substantial utility as intermediates for the formation of other organic compounds, both symmetrical and unsymmetrical.

These and further objects of the present invention will become more apparent as the description proceeds below and in connection with the appended claims.

The novel compounds of the present invention are divided into two classes. Formula 1 illustrates the general structural formula of the first class of such compounds:

In the above formula, R is selected from the group consisting of alkyl, alkenyl, aryl, aroyl, aralkyl, dialkyl (di-alkenyl) amino-alkylene (alkenylene), heterocyclic alkyl, alkoxyalkyl, alkoxyalkenylene, cycloalkyl and cycloalkenylene. Generally speaking, R may be represented by any member of the groups set forth above, provided only that the solubility and chemical stability of the reactant containing the R constituent which is used to form the compound of Formula 1 is such as to permit that reactant to react under the prevailing reaction conditions to form

the desired diazaspirane. Otherwise, there is no limitation as to the value of R.

Examples of preferred R substituents (though, as indicated, the broad classes listed are not so restricted) are as follows:

- (1) Alkyl: alkyl groups of 1-22 carbon atoms.
- (2) Alkenyl: alkenyl groups of 1-22 carbon atoms.
- (3) Aryl: phenyl; pyridyl; thiophenyl; furyl; quinolyl.
- (4) Aroyl: benzoyl; halobenzoyl.
- (5) Aralkyl: benzyl; fluorobenzyl; pyridylalkyl; phenylalkyl; benzhydryl; chlorobenzyl; isopropylbenzyl; benzylol.

(6) Dialkyl (dialkenyl) amino-alkylene (alkenylene): dimethylaminoethyl; diethylaminoethyl; dipropylaminoethyl; diethylenamino-hexyl; dihexylaminopropylene.

(7) Heterocyclic alkyl: pyrrolidino; piperidino; morpholino; N-alkyl piperazine; tetrahydrofuran; tetrahydropyran alkyl.

(8) Alkoxyalkyl: methoxypropyl; ethoxyethyl; methoxyhexyl.

(9) Alkoxyalkenylene: methoxyallyl; ethoxyallyl.

(10) Cycloalkyl: cyclohexyl; cyclopentyl; cyclohexylmethyl; cyclooctyl; cycloheptyl; cyclopropyl.

(11) Cycloalkenylene: cyclopentenyl; cyclohexenyl.

(25) The second class of compounds of the present invention are represented by Formula 2 below:

30 In Formula 2, R and R' are selected from the group consisting of hydrogen and any of the groups previously described as representing R in connection with the compounds of Formula 1, except that R and R' are never the same group. In other words, the 3,9-diazaspiro(5.5)undecane nucleus of Formula 2 is unsymmetrically substituted by the substituent groups previously enumerated.

The compounds of the present invention, and particularly those of Formula 1 in which one of the nitrogen substituents is hydrogen, are extremely valuable and versatile synthetic intermediates. For example, due to the unique activity of the hydrogen atom not possessed by the other substituents enumerated, this hydrogen may be selectively replaced by a wide variety of substituents, including all those defined in connection with R' in Formula 2 as well

45 as other reactive groups such as alkanols, epoxides, ureas, thioureas, or amides of pharmacologically active groups such as p-aminobenzoyl, diphenylacetyl, tropyl, benzoyl, which give rise to a wide variety of pharmacologically active products such as local anesthetics [i.e., para-amino benzoate ester of 3-methyl-9-hydroxyethyl-3,9-diazaspiro(5.5)undecane], antispasmodics [i.e., 3-benzyl-9-hydroxyethyl-3,9-diazaspiro(5.5)undecane tropate ester; 3-methyl-9 - benzyl-3,9-diazaspiro(5.5)undecane], antihistaminics [i.e., 3 - methyl - 9-(pyridylethyl)-3,9-diazaspiro(5.5)undecane], and hypotensives [i.e., trimethoxybenzoylamide of 3-methyl-3,9-diazaspiro(5.5)undecane].

In addition, the compounds of Formula 1 can be used to obtain the compounds of copending application Serial No. 47,613, as an alternative method of synthesis.

60 The compounds of the present invention may be prepared in a variety of ways. Among these methods of preparation are the following:

(1) Through reaction of the appropriate N-substituted piperidine 4,4-dicarboxylic acid esters with the appropriate primary amine, either at the reflux temperature of the mixture or in a pressure bomb as the properties of the amine may prescribe, followed by reduction to the corresponding N,N'-disubstituted diazaspirane.

(2) From the diazaspirane obtained in (1), when R' is benzyl or other high boiling arylamine, the desired N-substituted, N'-hydrogen amine may be obtained if desired by catalytically removing the N'-group.

(3) Alternatively, the N,N' unsymmetrically substituted diazaspirane may be obtained from N-substituted piperidine 4,4-dihaloethyl esters by ring closure with an appropriate primary amine.

The following examples will illustrate the preparation of exemplary compounds within the scope of the present invention.

Example I.—3-methyl-9-benzyl-3,9-diazaspiro(5.5)undecane

140 gm. (0.52 mole) of piperidine-1-methyl-4,4-diacetic acid diethyl ester was refluxed for 30-60 hours with a 4-5 molar excess of benzylamine. Excess benzylamine was distilled off and the residue heated to 200° C., at which temperature it was maintained for 2-4 hours. The residue was vacuum distilled and 65 gm. of material (B.P. 185-195° C./0.1 mm.) was obtained. This material, 3-methyl-9-benzyl-3,9-diazaspiro(5.5)undecane-8,10-dione, was reduced in absolute ether with lithium aluminum hydride. After decomposition of the lithium aluminum hydride-complex with water, filtration of the inorganic residue, drying the ether solution over sodium sulfate and stripping of the ether, the title compound was obtained by vacuum distillation of the residue and had a boiling point of 128-133° C./0.15 mm. There was obtained 51 gm. (87% yield) of the title compound (based on the dione).

The dihydrochloride of the title compound melted at 326-327° C.

Example II.—3-methyl-3,9-diazaspiro(5.5)undecane

This valuable intermediate was obtained from the compound of Example I by catalytic debenzylation. 43 gm. of 3-methyl-9-benzyl-3,9-diazaspiro(5.5)undecane was dissolved in methanol and made acid with concentrated hydrochloric acid. 4 gm. of 10% palladium catalyst on charcoal was added and the mixture hydrogenated at 50-60 p.s.i. at 80° C. for 24 hours. All solvents were stripped and the syrupy residue dissolved in a minimum of water and made alkaline with saturated sodium hydroxide solution. The water solution was extracted several times with ether since the base is miscible with water. The ether solution was dried over sodium sulfate and calcium hydride since the solution of the base in ether gels if water is present. After drying overnight, the ether was stripped and the residue distilled to yield the title compound (B.P. 128-130° C./15 mm.). This amine is a strong base, completely miscible with water and very rapidly absorbs carbon dioxide from the atmosphere to form a solid carbonate.

The dihydrochloride melted at 319-320° C.

Example III.—3-methyl-9-(3-dimethylaminopropyl)-3,9-diazaspiro(5.5)undecane

The amine, 3-methyl-3,9-diazaspiro(5.5)undecane, was readily alkylated to the title compound by treatment with dimethylaminopropyl chloride in refluxing toluene in the presence of a small amount of potassium iodide. The title base was obtained and boiled at 95-105° C./0.1 mm. Its trihydrochloride melted at 318-319° C.

While, as previously pointed out, the compounds of the present invention are superficially similar to those of co-pending application Serial No. 47,613 in that both are 3,9-diazaspiro(5.5)undecanes, there are significant distinctions between the compounds of the two applications. For example, the methods of preparation of the respective compounds are basically different from one another. In the method of forming the symmetrical compounds of Serial No. 47,613, ammonia or a primary alkyl or alkenyl amine

is reacted with the dianhydride of methane tetraacetic acid to form the corresponding bis-amic acid, the acid then being heated sufficiently to cyclize the acid to the bis-amide, the amide then being reduced to the corresponding diazaspirane. Such procedure, of course, results in a symmetrical diazaspirane, which would not be satisfactory to form the unsymmetrical diazaspiranes of the instant case. Furthermore, while it would superficially appear feasible to obtain the compounds of the present invention from the symmetrical bis-secondary amines of Serial No. 47,613, in practice this is not feasible. It is exceedingly difficult to substitute a desired radical for one of the N-hydrogens without doing so to the other. At best, a mixture of symmetrical and unsymmetrical diazaspiranes might result. Conversely, speaking, however, it is possible to prepare the compounds of Serial No. 47,613 starting with the unsymmetrical compounds of the instant case, particularly in the case where one of the nitrogen substituents of the starting compound is hydrogen.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A compound of the formula

wherein R and R' are each selected from a different one of the group consisting of:

- (a) hydrogen
- (b) lower alkyl
- (c) aralkyl selected from the group consisting of pyridyl lower alkyl and phenyl lower alkyl
- (d) di-lower alkylamino lower alkylene
- (e) hydroxy lower alkylene.
- 2. 3-methyl-9-benzyl-3,9-diazaspiro(5.5)undecane.
- 3. 3-methyl-3,9-diazaspiro(5.5)undecane.
- 4. 3-methyl-9-(3-dimethylaminopropyl)-3,9-diazaspiro(5.5)undecane.
- 5. The para-amino benzoate ester of 3-methyl-9-hydroxyethyl-3,9-diazaspiro(5.5)undecane.
- 6. 3-methyl-9-(pyridyethyl)-3,9-diazaspiro(5.5)undecane.
